DEVELOPING APPARATUS

Filed Oct. 26, 1927

Inventor:
Richard Fred Allin,
Cheever & Cox
Attest.

UNITED STATES PATENT OFFICE

RICHARD FRED ALLIN, OF NEW YORK, N. Y., ASSIGNOR TO EUGENE DIETZGEN COMPANY, OF CHICAGO, ILLINOIS, A CORPORATION OF DELAWARE

DEVELOPING APPARATUS

Application filed October 26, 1927. Serial No. 228,719.

My invention relates to apparatus for developing light-sensitive material such as paper films, textile material and the like, particularly light-copying paper, which are developed by the action of alkaline gases or alkaline solutions.

One of the objects of my invention is to provide an apparatus for developing a relatively long strip of light-sensitive material, such as paper, in a closed cabinet by means of developing medium, preferably developing gases, wherein the strip is fed in a continuous and uninterrupted manner through the cabinet, and the construction comprehends devices arranged to prevent the escape of the objectionable gases or fumes while permitting the passage of the strip to be developed through the cabinet.

Another object of my invention resides in the provision of a developing apparatus of the continuous type wherein the strip of material to be developed is fed uninterruptedly through the cabinet which contains the developing fumes, and wherein the entrance and exits for the strip passing through the developing cabinet are constructed and arranged to provide substantially gas type openings cooperating with the moving strip of material to be developed and which are arranged to prevent the escape of the gases at the openings while permitting the feed of the strip therethrough.

Still another object of my invention resides in the provision of a developing apparatus of the continuous type wherein the main developing chamber, in which the developing fumes are generated, is provided with auxiliary chambers at opposite ends through which the strip of material is adapted to uninterruptedly pass during the developing operation, and wherein the entrances and exits, both to the main chamber and the auxiliary chambers are formed to permit the strip to be fed therethrough, but which are constructed to prevent the escape of gases therefrom, the auxiliary chambers constituting airing chambers. An ancillary object resides in providing the discharge airing cabinet, at the discharge end of the apparatus, with a suction chamber adapted to remove

occluded gases from the developed paper so that such gases will not be discharged into the atmosphere of the developing apparatus.

Additional objects of my invention reside in the particular means disclosed for sealing the entrance and exit to the developing and airing chambers, while at the same time permitting the feed of the strip of material to be developed, or developed therethrough.

These and other objects of my invention will be apparent from a perusal of the following specifications when taken in connection with the accompanying drawing wherein,

The figure represents a side sectional view of the preferred form of my continuous type apparatus.

In general the light-sensitive type of paper which is adapted to be used in conjunction with my present invention is developed by means of either alkaline fumes or by means of contact with alkaline liquid, such as ammonia. I have illustrated my invention in connection with the development of the paper by means of alkaline gases or fumes generated within the chamber. In my present invention, the paper to be developed may be conducted directly from a printing machine so that the printed paper may be led directly from the printer into the developer, thus establishing continuous printing and developing; or it may be led directly from the printed roll. In the present instance I have illustrated the latter operation, but merely for convenience of description. In my present invention, the material to be developed is conducted in a continuous manner through the cabinet wherein the developing fumes are generated, the paper being developed as it passes through this chamber. The paper will be developed as it passes through the developing chamber at a rate of about 8 feet of paper per minute. The developed paper as it issues from the developing cabinet will be in a dry condition, so that the copy will be absolutely true and be free from wrinkles. At the same time, by reason of my improved invention, the developing will be carried on in a continuous manner and in such a way as to prevent the escape

of objectionable gases into the atmosphere adjacent to the apparatus, and this includes the elimination of occluded gases which tend to adhere to the surface of the paper as it issues from the machine. In this manner all traces of the developing gases in the vicinity of the apparatus are removed.

Referring now to the details of the drawing, my improved device comprises the supports 2 which may be of any desired type, and on which is mounted a relatively long horizontal cabinet 4 of desirable material. This cabinet is preferably provided with a removable top 6 which may be hinged there-to. In addition the cabinet is provided at its ends with partitions 8 and 10 and 12 and 14, arranged in pairs, the partitions 8 and 10 having openings therein adjacent to the top of the cabinet 4, and these partitions are disposed at the exit end of the cabinet. The partitions 12 and 14 have their openings arranged adjacent to the bottom of the cabinet and these partitions are disposed at the inlet end of the machine. For convenience of illustration, I show the front part of the cabinet as provided with a feeding table 16 attached thereto and provided with a bracket arm 18 for roll 20 of the paper which has already been printed and which is already to be developed. Alternatively, this feeding table may be replaced by the printed machine itself so that the paper 20 may enter directly from the printing machine into the developing cabinet 4. At the entrance end of the cabinet 4 I have provided a roll 22 under which the paper to be developed passes. The openings in the partitions 12 and 14 are directly opposite the underside of this roll 22.

The space between the partitions 12 and 14 is arranged to provide an ante chamber or airing chamber which comprises a chamber of double walled construction whereby to prevent the escape of gases or fumes in the developing chamber to the outside of the machine through the inlet openings for the feed paper.

I have provided these openings in partitions 12 and 14 with means for preventing the escape of the gases from the developing chamber through these openings, while the light-sensitive material to be developed is passing therethrough. While this means may comprehend a number of constructions adapted to be associated with and cooperated with the strip of light-sensitive paper traveling therethrough, I prefer to utilize the means shown in my present drawing, since the same comprehends a most simple, yet effective, arrangement for accomplishing this article. To this end I have provided the partition 14, which is the outermost partition at the entrance end of the machine, with a hanging door 24 which is pivoted at 26 to the bottom edge of the partition 14. The lower edge of this hanging door 24 is provided with

a packing or gasket of preferably resilient or yieldable material, such for instance as rubber, or even felt may suffice, which is adapted to drag or wipe against or along the upper face of the strip of material which is passing through whereby to form a sealed contact with said face so as to prevent the escape of the gases therethrough. This door 24 is held against the traveling strip by means of a coiled spring 28. I have sealed the lower face of the traveling strip of material 20 by means of an upstanding partition 30 preferably secured to the lower portion of the partition 14, and which partition 30 is edged along its top where the similar gasket or packing 32 contacts with the underside of the continuous traveling strip of paper to be developed. In this manner this sealed opening or gas type inlet permits the feed or passage of the paper 20 therethrough, while at the same time prevents the escape of the gases therethrough.

The opening in the partition 12, which forms the other wall of the ante chamber at the front of the machine, is likewise provided with means for prevention of the gases therethrough, while permitting the feed or passage of the traveling strip of paper therethrough. In this instance I provide the front of the partition wall 12 with a relatively wide block 34 formed on its face with a relatively wide and thick packing or sealing strip or gasket of suitable material 36 such as rubber or the like which may yield, but which at the same time grips and hugs the traveling strip of paper or material passing thereby and prevents the escape of gases along the underside of this paper and out through this opening. Cooperating with this packing 36 I provide an upper block 38 of some weight arranged to slide between the partition 12 and the guide 40, which block 38 has its under surface faced with a relatively wide and thick strip of rubber or other yieldable packing material suitable to prevent the escape of the gaseous developing fumes and not being corroded or affected thereby. Since this block is gravity operated it will press at all times with sufficient force upon the upper surface of the material or strip being developed so as to prevent the passage of the gases through the opening and during the inward travel of the strip 20. This construction is peculiarly effective because of the yieldable nature of the packing 36 on the end of block 34, and the similar packing on the under surface of the gravity actuated block 38. If desired blocks 34 and 38 may be pressed toward each other resiliently as by means of a spring instead of gravity. The weight of the block 38 is sufficiently selected to permit the feed of the strip, yet, at the same time effecting a gas tight seal.

The inner chamber of the cabinet 4 constitutes the developing chamber. It is rela-

tively long and is provided with a relatively shallow pan 42 containing the developing liquid for generating the developing fumes. This developing chamber contains one or 5 more guide rollers 44, and 46 and the plurality of guide bars 48, which, as shown, are distributed therein in a manner so as to cause the paper strip 20 to wind back and forth in the developing chamber as it travels over the pan 42 which generates the gaseous fumes. These fumes rise to the top of the chamber, and for this reason the entrance for the paper 20 is located at the lower portion 10 of the chamber, while the exit is located at the top of this chamber. The exit end of the apparatus is constructed substantially like the entrance end, except that I prefer to reverse the disposition and arrangement of the sealing means through the partitions 8 and 15 20; that is, in this instance I have shown the gravity actuated block 50, and the under block 52, with their yielding packing facings, as sealing the opening in the outermost partition 10 and the innermost partition 8 as being provided with a pivoted mounted door 54, faced with a gasket and provided with a coiled spring 56 for keeping the door in normally upright position with the packing directly against the underside of the discharging paper strip 20, and the stationary strip 56 edged with a similar gasket 58 wiping against the upper side of the discharging strip 20. It must be appreciated that I may reverse this arrangement of sealing means 25 30 to accord with the arrangement shown at the entrance end of the machine as desired. The space between the partitions 8 and 10, at the inside end of the machine, constitutes an airing chamber and permits the occluded gases 35 to be wiped partially from the developed strip. In this instance the first packing members 56 and 58 will wipe practically all of the 40 45 occluded gases from the surface of the strips, and will prevent them from entering the airing chamber, while the second sealing means 50 and 52 will catch the greater part of the residue of these occluded gases, and will retain them in the airing chamber. In this connection it will be understood that the arrangement of the sealing gaskets, while permitting the discharge of the strip therethrough, will in the main practically prevent the escape of any gases therethrough; those gases which do escape will be by reason of 55 60 65 occlusion.

In order to practically remove any and all traces of the occluded gas, I have disposed at the exit end of the strip 20, adjacent the partition 10, a second airing chamber which includes an overhead funnel-shaped hood 54, which leads to a section device for removing any gases. The extreme end of this hood is open to permit the discharging strip 20 to be wound about any type of winding device 56. 65 This winding device constitutes a rotatable

drum or reel driven by means of the belt 58 from the motor 60. In the normal operation of the device, when the motor 60 is started, the drum or reel 56 will be rotated whereby to draw the strip of paper 20, which has been threaded or wound thereon, as by means of a lever, as is well known in the art, through the developing chamber, and as the strip passes uninterruptedly therethrough, it will be developed by the generation of the developing gases, and as hereinbefore pointed out, these gases will be confined within the developing chamber, and will not escape through the inlet and exit openings of the machine. At the same time any occluded gases which chance to pass out through the machine are removed by means of a suction device 54.

It will be apparent that, instead of using gases for the source of development, I may provide means for applying generating liquid to the traveling strip of paper and utilize inlet and exit packing means for preventing the escape of gases generated within this chamber, but I prefer in this continuous process with my present type of machine, to develop by means of the gases, because the paper remains dry, will not run and will not wrinkle.

It will be apparent that I have provided a most simple, yet effective type of device for continuously developing long strips of printed light-sensitive material, such as paper of the type indicated and that by reason of the novel feeding arrangement, in connection with the inlet and exit openings, I have prevented the escape of the developing gases during the travel of the strip through the machine. It will also be apparent that by reason of my continuous machine, I am enabled to combine the machine with the present type of printing machine whereby the printed paper may pass directly from the printing machine into and through the developing machine, and be delivered in a dry, unwrinkled condition and free of developing gases, while at the same time the escape of the developing gases, along this continuous process, is prevented.

It will thus be seen that in accordance with my present invention, I am enabled continuously to feed along a long sheet or continuous strip of paper to be developed, while subjecting it to gaseous developing fumes as it travels and then subsequently to remove substantially all of the occluded gases from the face of the developed strip as it passes along, as by wiping members which not only remove these occluded gases, but prevent their escape, and thence I am enabled to pass the developed strip through an isolated body of air which, in the apparatus set forth, constitutes the airing chamber or chambers, and one of these chambers may be provided with suction means for positively removing or sucking any residual gases which may hap-

pen to be present on the surface of the paper. In this manner the developed paper will be practically free of any of the developing fumes as it passes from the developing apparatus.

Having thus described my invention what I claim as new and desire to secure by Letters Patent is:

1. In a device of the class described, the combination of a cabinet having a developing chamber, means for providing said chamber with developing gas, an airing chamber located adjacent said developing chamber, said developing chamber and said airing chamber having communicating openings for the passage of light-sensitive sheet material therethrough, means for feeding said material uninterruptedly through said chambers in sequence, and means associated with the openings for said chambers for preventing the escape of gases therethrough while permitting the passage of the material.

2. In a device of the class described, the combination of a cabinet provided with partitions forming an intermediate chamber and auxiliary chambers at the ends thereof, said partitions having openings therein, the openings at the entrance partitions being adjacent to the bottom of the intermediate chamber and the openings at the opposite end being adjacent to the top of the intermediate chamber, means in said central chamber providing developing gas, a power driven winding reel adapted to have a strip of light-sensitive material wound thereabout whereby to feed the strip of paper through said chambers and through the openings thereof, the openings of said chambers being faced with packing material, adapted to engage the opposite faces of the strip as it passes therethrough, and means for yieldingly pressing one of said packing faces toward the other.

3. In a device of the class described, the combination of a cabinet having partitions forming a developing chamber, an airing chamber and an exhaust chamber in sequence, means for uninterruptedly passing sensitive sheet material through said developing chamber, said airing chamber, and through said exhaust chamber, means for creating an atmosphere of a suitable developing gas in said developing chamber, means for engaging the opposed faces of said sheet as it passes from said developing chamber into said airing chamber to remove the occluded gases and to prevent the escape of gases from said developing chamber and means engaging the opposed faces of said sheet as it passes from said airing chamber into said exhaust chamber for preventing the escape of gases from said airing chamber, and means connecting with said exhaust chamber for removing the escaping gases therefrom.

4. In a developing apparatus, in combination with a developing chamber containing

developing gas, of means for feeding a sheet of light-sensitive material through said developing chamber, means for passing the developed sheet between yieldable wiping members for removing occluded gases from the sheet, and means for passing the developed sheet through an airing chamber.

5. In an apparatus for developing light sensitive material by the action of chemically active gas, the combination of means forming a cabinet provided with a developing chamber containing a developing gas, means for passing light sensitive sheet material in a predetermined path therethrough so as to be acted upon by the gas, and a hood having a connection to a suction exhaust for removing the gas escaping from the cabinet with the developed light sensitive material.

6. In an apparatus for developing light sensitive material by the action of chemically active gas, the combination of means forming a cabinet provided with a developing chamber containing a developing gas, means for passing light sensitive sheet material in a predetermined path therethrough so as to be acted upon by the gas, and a hood disposed immediately over the discharge of said cabinet, said hood having a connection with a suction exhaust to remove escaping gas.

7. In a device for developing light sensitive material by the action of a chemically active gas, the combination of means forming a substantially air-tight developing chamber, means associated with said chamber for passing light sensitive material therethrough, means for subjecting the material while passing through said chamber to the action of a developing gas, and means for airing the developed sheet material after passing through said gas.

8. In a device for developing light sensitive material by the action of a chemically active gas, the combination of means forming a substantially air-tight developing chamber, means associated with said chamber for passing light sensitive material therethrough, means for subjecting the material while passing through said chamber to the action of a developing gas, and means for sucking occluded gases from said developed sheet material after passing through said gas.

9. An apparatus of the character described comprising two compartments, means in one of said compartments for generating developing gas, means for continuously drawing paper to be developed through both said compartments, sealed means through which the paper is introduced into and removed from the developing compartment, and means in the second compartment for removing from the paper any developing gas adhering thereto.

10. In a device of the class described, the combination of a cabinet having partitions forming a developing chamber and an airing

chamber, means for uninterruptedly passing light sensitive sheet material through said developing chamber and through said airing chamber in sequence, means in the developing chamber for creating an atmosphere comprising ammonia fumes in the developing chamber, means engaging the opposed faces of said sheet as it passes from said developing chamber into said airing chamber for the purpose of wiping from the sheet material gases clinging thereto and to prevent the escape of fumes from the developing chamber and means engaging the opposed faces of said sheet material as it is discharged from the airing chamber for preventing the escape of gases from said airing chamber.

In witness whereof, I have hereunto subscribed my name.

RICHARD FRED ALLIN.
